United States Patent Office

Des. 218,905
Patented Oct. 6, 1970

218,905

SET OF PLAYING CARDS

Donald J. Brown, 542 E. Los Angeles Drive,
Vista, Calif. 92083

Filed Oct. 29, 1968, Ser. No. 14,211

Term of patent 14 years

Int. Cl. D21—01

U.S. Cl. D34—13

FIG. 2.

FIG. 1.

FIG. 3.

FIG. 1 is a face view of each one of sixteen cards in a set of playing cards showing my new design;

FIG. 2 is a face view of each one of sixteen other cards in the set; and

FIG. 3 is a face view of each one of sixteen other cards in the set.

The back of the cards are conventional.

I claim:

The ornamental design for a set of playing cards, as shown and described.
